UNITED STATES PATENT OFFICE.

AARON E. YETTER, OF KNOXVILLE, IOWA.

PUMP.

Application filed July 21, 1926. Serial No. 124,020.

My present invention has reference to a centrifugal pump of a construction whereby liquid may be elevated and distributed at a comparatively high rate of speed and in great volume so that the device is especially useful for irrigating purposes, but may also successfully be used in draining coffer-dams, handling muddy and gritty water, oils, tars and other heavy liquids as the improvement makes use of no plungers or other parts that will be injured by contact with such fluids.

An object is to provide a comparatively simple and thoroughly efficient pump in which water or like fluid is elevated from a well or other source of supply, discharged into a suitable receiving tank without the employment of plungers, sucker rods and similar actuating devices.

20 A further object is the provision of a centrifugal pump in which a tubular member or casing is let in a fluid body and which has a normally closed inwardly open valve in the bottom thereof, there being supported 25 on and in longitudinal alignment with said pipe a second pipe which is revoluble and which is supported in a novel manner to effect the least amount of friction between the said pipes and the supports therefor, the 30 last mentioned pipe having its upper end received in a basin provided with a suitable outlet and its said end being formed with a nozzle whose passage is valve controlled, means being provided for priming the well 35 pipe, and means being also provided for revolving the fluid ejector pipe at desired speeds and in opposite directions, whereby the revolving of the said ejector pipe and the nozzle associated therewith will start the 40 fluid from the well and thereafter the said fluid will be continuously elevated and ejected.

A further object is the provision of a centrifugal pump that shall comprise comparatively few simple parts, easily associated to produce an operative structure that may be cheaply set up or removed as occasion requires.

To the attainment of the foregoing and 50 other objects which will present themselves as the nature of the invention is better understood, the improvement resides in certain novel features of construction, combination and operative association of parts, 55 one of a number of satisfactory embodiments

of which is disclosed by the accompanying drawings.

In the drawings:

Figure 1 is a side elevation of the improvement.

60 Figure 2 is a sectional view, on an enlarged scale, approximately on the line 2—2 of Figure 1.

Figure 3 is a detail sectional view approximately on the line 3—3 of Figure 2.

65 Figure 4 is a longitudinal sectional view through the nozzle.

By way of explanation I have illustrated my improvement in use with a dug well, it being, of course, understood that the same 70 may be successfully employed for elevating other fluid bodies.

The pipe through which the fluid is elevated or what I will term the well pipe, is indicated in the drawings by the numeral 1. 75 The lower end of this pipe extends below the level of the fluid in the well 2 and this end of the pipe has screwed thereon a casing 3 whose bottom wall is open but provides a seat for the ball valve 4. The movement 80 of the valve 4 when unseated, is limited by a laterally extending element 5 in the casing 3. The pipe 1 extends above the well, the said well in the showing of the drawings being closed by a concrete top 6 and on this 85 concrete body there is fixed a metal plate 7 having a central boss 8 through which the well pipe 1 passes. A binding element 9 passes through the boss and contacts with the well pipe. Screwed on the well pipe 90 and resting on the boss 8 there is a coupling 10 and screwed in the angle branch of this coupling there is a pipe 11 coupled to a vertical extension 12 provided, at its outer end, with a funnel member 13. The passage 95 through the pipe 12 is controlled by a hand operated valve 14. Fluid is let in the funnel and directed through the pipe members 12 and 11 into the well pipe when the pump is to be primed.

100 On the disc or plate 7, and secured thereto by the means 16 that holds the said plate or disc on the body 6 there are the angle ends or foot portions of the upright members 17 of a metal frame. The uprights 17 105 are connected and held in spaced relation through the medium of brace plates 18 and 19. The members 18 and 19 have downwardly extending flanges which contact with the uprights and through these flanges and up- 110

rights there are passed securing means. The lower horizontal brace plate has a depending yoke-like portion or frame 20, the lower element of which is centrally formed with 6 an upwardly directed boss 21, and in the lower end of this boss, the upper end of the well pipe 1 is received. Also received in this boss there is the lower end of a tubular shaft 22. Preferably there are anti-frictional 10 bearings between the confronting ends of the tubular shaft 22 and the well pipe 1, and the boss 21 provides a box having packing 23 that surrounds the confronting ends of the tubular members 22 and 1. The packing 15 is held in the box by a cap member 24 which is adjustably secured, by means 25, on the boss or packing box 21. The tubular shaft 22 has fixedly secured thereon a flange 26 that is received in a flanged sleeve 27 20 which is screwed into a central opening in the brace plate 18. Between the flange 26 and the sleeve 27 there are anti-frictional balls 28.

The brace plate 19 also has a central 25 threaded opening therethrough in which is screwed a depending flange sleeve 29, that is also preferably fixed to the said plate 19. Fixed on the tubular shaft 22, and received in the sleeve 29 there is a flange 30, and between this flange and the sleeve there are 30 anti-frictional balls 31.

Fixedly secured on the flanged top of the frame 17 there is the closed bottom of a basin 32. This basin has its bottom provided with 35 a central opening that is surrounded by an upwardly directed flange 33 through which the tubular shaft 22 passes. The basin 32 has one of its sides provided with an outlet opening that is surrounded by a fixed spout 34. The top of the tubular shaft 22 is 40 flanged and bolted to this flange there is the flanged end of an angle coupling 35 and secured to the outer flange of the coupling 35 there is the flanged inner end of a nozzle 36. 45 The outer discharge end of the nozzle is reduced, and is indicated by the numeral 37. In and adjacent to the flanged end of the nozzle there is preferably integrally formed a spider 38 and slidably in the nozzle and 50 normally contacting the spider there is a tubular piston 39. The inner end of the piston is wholly open, but the outer end thereof is flanged, as at 40, to provide a central opening. The wall provided by this 55 opening is flared and provides a seat for a valve 41. A helical spring 42 is connected centrally between the valve 41 and the spider 38.

Fixed on the tubular shaft 22 there is a 60 fly wheel 43, and fixed above the fly wheel there is a pulley wheel 44. Trained around the pulley wheel there is a belt 45 that is operated by any suitable source of power (not shown). In this connection it should 65 be stated that other means for revolving the

tubular shaft 22 may be employed, as for instance, there may be fixed on the said shaft a toothed wheel which is in mesh with a train of wheels whose shafts are supported on suitable elements connected to the frame 70 17, and one of these gears may be provided with a handle whereby the tubular shaft 22 may be manually operated.

The pump is primed by pouring a fluid 75 into the funnel but the valve controlled slideable piston in the nozzle renders the pump self-starting. This is accomplished by revolving the pump so that the centrifugal force will cause the piston to move outwardly in the nozzle. The outward movement 80 of the piston is limited by its contact with the shoulder 46 arranged in the barrel adjacent to its reduced outlet end. In such outward movement the valve 41 holds the piston closed so that a vacuum or suction 85 is thus created. The pump is then slowed down which permits the spring 42 to influence the piston and its valve in an opposite direction and to initial position. Thus by speeding and slowing down the pump the piston will be caused to move in opposite 90 directions in the nozzle and thereby create sufficient suction or a sufficient vacuum to draw water through the pump and through the nozzle. When the water is flowing and the pump is revolved at a definite speed the 95 force of water against the piston will have moved the said piston against the stop shoulder 46 and such force of water will hold the valve 41 opened. When the pump is not 100 in operation the piston will, through the medium of the spring 42, return to initial position

My improvement is of a comparatively 105 simple nature and, as previously stated, may be easily erected or dismounted when not desired as a permanent fixture. With the improvement a large volume of fluid can be elevated and delivered through the outlet 110 34 in an easy and expeditious manner, and the flow of the fluid through the pipe can be regulated by the velocity in which the tubular shaft 22 is operated. The improvement, is, of course, susceptible to changes 115 and modifications and therefore, I do not 120 wish to be restricted to the precise structural details herein set forth as I hold myself entitled to make such changes therefrom as fairly fall within the scope of what I 125 claim without departing from the spirit of the invention or sacrificing any of the advantages of the invention.

Having described the invention, I claim:—

1. A centrifugal pump including a well pipe having its lower portion arranged in 125 a body of fluid and an inwardly opening valve at the bottom of said pipe, a tubular shaft arranged above and in a line with the well pipe, packing between the shaft and pipe, anti-frictional bearings supporting the 130

tubular shaft and holding the same from longitudinal movement, a nozzle arranged at an angle on the outer end of the tubular shaft, means for revolving the shaft, a tubular piston in the nozzle, an outwardly movable valve for the piston, a spring fixed at one end of the nozzle connected with the valve and urging the valve in a direction to close the tubular piston and to urge the piston toward the axes of the shaft, and means limiting the sliding movement of the piston in the nozzle

2. A centrifugal pump, including a pipe let in a fluid body, a casing on the lower end of the pipe, an inwardly opening valve controlling the inlet to the casing, a tubular shaft arranged on and in longitudinal alignment with the pipe, anti-frictional elements between the shaft and pipe, a stuffing box between the shaft and pipe, anti-frictional bearings supporting the tubular shaft and holding the same from longitudinal movement, a fly wheel on the tubular shaft, means for revolving the shaft, a nozzle on the outer end of the shaft, said nozzle having a reduced outlet end, a spider in the nozzle, a hollow piston in the nozzle, a valve for closing the outlet end of the piston, a spring for the valve connected with the spider, a basin in which the nozzle is received, said basin having an outlet spout, and valve controlled means for priming the pump.

3. A centrifugal pump, including a pipe let in a fluid body, a casing on the lower end of the pipe, an inwardly opening valve controlling the inlet to the casing, a tubular shaft arranged on and in longitudinal alignment with the pipe, anti-frictional elements between the shaft and pipe, a stuffing box between the shaft and pipe, anti-frictional bearings supporting the tubular shaft and holding the same from longitudinal movement, a fly wheel on the tubular shaft, means for revolving the shaft, a nozzle on the outer end of the shaft, said nozzle having a reduced outlet end, a spider in the nozzle, a hollow piston in the nozzle, a valve for closing the outlet end of the piston, a spring for the valve connected with the spider, a basin in which the nozzle is received, said basin having an outlet spout, and valve controlled means for priming the pump.

ing the outlet end of the piston, a spring for the valve connected with the spider and a valve controlled pipe for priming the pump.

3. A centrifugal pump, including a pipe let in a fluid body, a casing on the lower end of the pipe, an inwardly opening valve controlling the inlet to the casing, a tubular shaft arranged on and in longitudinal alignment with the pipe, anti-frictional elements between the shaft and pipe, a stuffing box between the shaft and pipe, anti-frictional bearings supporting the tubular shaft and holding the same from longitudinal movement, a fly wheel on the tubular shaft, means for revolving the shaft, a nozzle on the outer end of the shaft, said nozzle having a reduced outlet end, a spider in the nozzle, a hollow piston in the nozzle, a valve for closing the outlet end of the piston, a spring for the valve connected with the spider, a basin in which the nozzle is received, said basin having an outlet spout, and valve controlled means for priming the pump.

In testimony whereof I affix my signature.

AARON E. YETTER.
